(57) **CLAIM**

The ornamental design for a gardening tool, as shown and described.

DESCRIPTION

FIG. 1 is a left side perspective view of a gardening tool according to our new design, showing a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of FIG. 2;

FIG. 9 is an enlarged view of FIG. 3;

FIG. 10 is a left side perspective view of a second embodiment;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is an enlarged view of FIG. 12; and,

FIG. 18 is an enlarged view of FIG. 13.

The superimposed areas with broken lines, shown in FIG. 8, illustrate portions of the gardening tool and form no part of the claimed design. The broken lines, shown in FIG. 17, illustrates portions of the gardening tool and form no part of the claimed design.

1 Claim, 10 Drawing Sheets
